UNITED STATES PATENT OFFICE.

WILLIAM H. LESTER, OF ELGIN, ILLINOIS, ASSIGNOR TO ELGIN AMERICAN MANUFACTURING CO., OF ELGIN, ILLINOIS, A CORPORATION OF ILLINOIS.

DESIGN FOR AN ARTICLE HOLDER.

Application filed August 19, 1925. Serial No. 14,520. Term of patent 3½ years.

To all whom it may concern:

Be it known that I, WILLIAM H. LESTER, a citizen of the United States, residing at Elgin, in the county of Kane and State of Illinois, have invented a new, original, and ornamental Design for Article Holders, of which the following is a specification, reference being had to the accompanying drawing, forming part hereof.

The figure is a perspective view of an article holder showing my new design.

I claim:

The ornamental design for an article holder, substantially as shown.

WILLIAM H. LESTER.
